CLAIM

I claim the ornamental design for a ring, as shown and described.

DESCRIPTION

FIG. 1 is a perspective view of a ring showing my new design;

FIG. 2 is a front elevational view thereof;

FIG. 3 is a side elevational view thereof, the left and right sides being identical;

FIG. 4 is a bottom plan view thereof;

FIG. 5 is a top plan view thereof; and,

FIG. 6 is another perspective view thereof.

The broken lines are for illustrative purposes only and form no part of the claimed design.
